UNITED STATES PATENT OFFICE

MELVIN O. JENNINGS, OF LEXINGTON, MASSACHUSETTS, ASSIGNOR TO HARRY H. BECKWITH, OF BROCKLINE, MASSACHUSETTS

SHOE HEATER

Application filed December 6, 1930. Serial No. 500,553.

This invention relates to apparatus for heating portions of box toes prior to the bed lasting operation. In the manufacture of shoes it is customary to use a stiffener in the toe to preserve the shape of the toe portion of the shoe and to protect the wearer. Many of these stiffeners are made of sheets of fibrous material mixed with a thermoplastic binder which at ordinary temperatures is relatively stiff and hard. After the shoe upper, with a box toe stiffener, has been attached to the last, the edges of the stiffener which have been turned under the last must be heated to enable the operator to make a smooth job of the lasting operation. It is also usually advantageous to reheat the whole box toe stiffener to some extent to make it set in the desired shape with no residual tendency to spring back toward its original flat shape. In heating box toes, the presence of a certain amount of moisture is usually desirable to prevent overheating the stiffeners and to prevent the thermoplastic constituent from "frying out" of the stiffener. On the other hand, with delicate leathers and certain fabrics such as moire, the amount of moisture present must be very slight, otherwise the upper will be damaged. According to the present invention, I supply apparatus by which the moisture may be regulated both as to the quantity and as to temperature so that the most delicate leathers and fabrics can be heated without injury. The apparatus also contains several other advantageous features of construction which will be apparent to one skilled in the art from the description of the invention which follows, and from the drawings, of which,—

Figure 1 is a perspective view of the upper portion of a shoe heater embodying the invention.

Figure 2 is a sectional view on a vertical plane of the heater shown in Figure 1.

Figure 3 is a perspective view of the steam box or heater block employed in the heater shown in Figure 1.

Figure 4 is a section on the line 4—4 of Figure 2.

Figure 5 is a fragmentary elevation of the steam box shown in Figure 3.

Figure 6 is a sectional view of the steam box on the line 6—6 of Figure 3.

Figure 7 is a perspective view of a modified form of shoe heater embodying the invention.

Figure 8 is a transverse section of the heater shown in Figure 7.

Figure 9 is a section on the line 9—9 of Figure 8.

Figure 10 is a section on the line 10—10 of Figure 8.

Figure 11 is a perspective view of the steam box employed in the heater shown in Figure 7.

Referring to the drawings in detail, Figures 1 to 6 illustrate a heater comprising an outer housing or casing 10 having a narrow upper portion 11 to receive the toe portions of partly constructed shoes for heating. The upper housing 11 has stationary rear and end walls, but the top and front wall are hinged to the lower housing so as to swing clear and open up the interior of the upper housing 11. The front and a portion of the top are normally closed in by a member 12 to which is hinged a top member 13. The latter may be operated as a damper by a convenient handle 14. The front wall portion 15 of the member 12 has arched openings to receive the toe portions of men's shoes. A masking plate 16 may be located against the outer face of the front wall, the plate 15 having arched openings of a size to receive women's shoe toes. This plate may be hinged to the member 12 (Figure 7) as by hinges 17 so that it is always at hand when not in use and may be easily and quickly swung into position. The member 12 may be connected as by hinges 18 to the lower housing so that this member, with the damper 13 and the plate 16, may be swung clear to open up the upper housing.

Within the casing 10 a steam box 20 may be mounted as on suitable brackets 21. As shown in Figure 3, the front and rear faces of the steam box may be provided with a series of ribs 22 which may be arranged diagonally across the faces of the box to present

greater radiating surface for the heat. On the front face of the box the lower portions of these ribs may be cut off to form a longitudinal channel 23 to facilitate the even distribution of steam which issues through small apertures 24 in the front wall of the box near the bottom thereof. The top of the box 20 may be formed with longitudinal ribs 25. Rising from the top of the box 10 there may be a series of arched walls 26 forming receiving chambers for the toes of the shoe lasts. The upper portions of these arched walls are preferably made hollow as at 27 so that steam may be admitted thereinto. 15 As shown in Figure 4 the walls 26 are cut away as at 28 toward the rear so as to facilitate the flow of air and moisture through the heating chambers and upwardly past the open damper 13. The steam supply may be 20 arranged as indicated in Figure 2, a supply pipe 30 being connected with an uptake 31 communicating with the hollow 27 between the double walls of the top of the arches 26. At the further end of the hollow a connecting 25 passage 32 leads downwardly into the steam box 20. The latter is preferably formed with a series of baffles 33 and 34 which provide a tortuous passage for the steam back and forth through the steam box to a discharge pipe 35. Thus the box may be effectively heated, the heat being radiated through from the upper ribs 25 and the front and rear ribs 22 as well as downwardly from the tops of the arches 26. 30 In order to provide moisture for conditioning the shoe toes, steam may be introduced through a supply pipe 40 into a lower compartment 41 of the steam box 20, this lower compartment being separated from the upper 35 part of the box as by a partition 42. This partition is heated by the steam flowing through the upper part of the steam box and thus helps to keep the steam in the lower compartment dry and hot. From the compartment 41, the steam issues through apertures 24 into the transverse channel 23 and thence upwardly through the grooves between the ribs 22. As the ribs 22 are kept hot by the steam in the upper portion of the steam 40 box 20, the steam passing between the ribs 22 is subjected to a further heating before it reaches the toes of the shoes to be heated. The steam supply for the upper and lower portions of the steam box may be readily controlled as by valves 43 and 44 in the steam pipes 30 and 40 respectively. 45 In order to obtain a supply of air for mixture with the steam and to regulate the amount of air thus mixed with the steam, the front wall of the casing 10 may be formed with a series of apertures 45. These apertures open into a chamber 46 between the front wall 47 and an inner partition 48 which rises upwardly from the bottom of the steam box part way up its front face. Between the

walls 47 and 48 a suitable damper 50 is mounted to control the flow of air through the apertures 45. The air passing into the chamber 46 flows upwardly past the damper 50 and mixes with the steam rising in the grooves between the ribs 22. This mixture of steam and air thus flows into the forward ends of the arched shoe receiving chambers and impinges on the bottoms of the toe portions of the shoe lasts inserted into the heating chambers. The portions of the shoe uppers which are turned under the edges of the shoe last and which thus lie against the bottom of the last are thus heated by a flow of air and steam which can be regulated to supply any desired percentage of moisture. At the same time the tops of the toes are also heated by radiation from the hot arched ceiling of the shoe receiving chambers. This heat radiation from above effectively prevents the condensation of any moisture on the shoe upper. By manipulation of the dampers 13 and 50, and the valves 43 and 44, the moisture and temperature of the heating devices may be suitably regulated to operate with maximum efficiency on any kind of fabric used for shoe uppers, including such easily damaged fabrics as artificial snakeskin, moire and the like. 70 75 80 85 90 95

In order to support the heel portions of the lasts when the toe portions are projecting into the heating chambers, I may provide a simple rack in the form of a rail 51. This rail may be pivotally connected at its ends to a pair of ears 52 secured to the rear wall of the housing 10. The rail 51 may be adjustably supported at any desired height relative to the shoe receiving openings, as by a pair of brackets 53 on the end walls of the housing 10. These brackets may each be supported by a spring 54 which presses an upright edge of the bracket against the rail 51. This edge, thus presented, is suitably notched so that the rail is adapted to enter any of the notches according to the height of adjustment desired. 100 105 110 115

Figure 7 illustrates a modified form of the invention. The heater shown therein comprises a housing 10 with a narrow upper portion 11 adapted to receive the toe portions of the shoe lasts for heating, and a top damper 13, as hereinbefore described. A masking plate 15 is also provided to take care of women's shoes as well as men's. Within the upper housing 11 of the housing 10, I may attach to the member 12 a series of arched members 60 forming chambers for the reception of shoe toes to be heated. These arched members may be cut away at their rear portion, as at 61, to provide ample draft upwardly past the damper 13. Beneath the arches 60 is a floor 62 which may be provided with suitably shaped apertures 63 to permit the flow of moist hot air from a compartment below upwardly against the under turned edges of the shoe uppers on the lasts. The 120 125 130

apertures 63 may be in the shape shown in Figure 9 to follow approximately the outline of the toe of the last, or may be in any other shape desired. The member 12 may be 5 hinged to the lower housing as by hinges 17 so as to be swung clear, if desired, together with the damper 13 and the inner arches 60. This exposes the floor 62 for ready access so that it can be used for conditioning flat box- 10 toe blanks. Beneath the floor 62 a steam box 64 is mounted on suitable brackets 65. The box is provided on its upper surface with longitudinal ribs 66 to increase the radiating surface and, front and rear faces with ribs 15 67 for the same purpose, the effect being increased by arranging the ribs diagonally instead of vertically up and down. The bottom face of the box is preferably concaved slightly as at 68, the bottom being provided with a 20 series of small perforations 69 through which steam may escape from the interior of the box. Resting on the bracket 65 is an open top pan 70 in which the steam box rests. The bottom of the pan 70 may be bulged down- 25 wardly so as to provide a distributing space under the steam box for the even distribution of steam longitudinally of the box. The steam issuing from the box escapes forwardly under the forward bottom edge of the box 30 into the grooves between the ribs 67. As it passes up in these grooves, it is heated by contact with and radiation from the ribs. The steam thus rising through the grooves between the ribs 67 may be mixed with a 35 quantity of air which can be regulated by a damper 71. This air may be admitted through a series of openings 72 in the front wall of the housing 10, the air entering a chamber 73 between the front wall 72 of the 40 housing and the forward wall of the pan 70. The damper 71 may be conveniently adjusted at any desired angle of opening, as by a suitable handle 74. Steam may be supplied to the steam box 64 as by a supply pipe 75, 45 the interior of the box being preferably formed with baffle plates 76 to lead the steam in a tortuous path starting with the top of the box and working down to the bottom, where the steam is discharged through the 50 openings 69 so that it can travel up the forward face of the box and pass into the shoe heating chambers.

I claim:

1. A shoe heater comprising a casing with 55 openings in the front wall of the upper portion thereof to receive toe portions of shoe lasts, a damper in the top of said casing extending from one end to the other thereof, a steam box in the lower portion of said casing, said box having a ribbed front wall and steam vents through the lower portion thereof, the lower portion of said casing having a chamber therein in front of said steam box and openings in said front wall leading into 60 said chamber, and a damper between said

chamber and the upper portion of said casing.

2. In a shoe heater, a steam box having its front wall formed with ribs, a partition member within said box forming separate 70 upper and lower steam chambers, baffle plates in said upper chamber to direct the steam in a tortuous flow, steam supply connections for both said chambers, and a steam exhaust connection for said upper chamber, said box 75 having vents from said lower chamber at points below said ribs.

3. In a shoe heater, a steam box comprising a rectangular portion and arched members extending upwardly from the top of said portion to form shoe receiving chambers, said arched members being double-walled to form a steam jacket above said chambers, a steam supply connection at one end of said jacket, a connecting passage from the other end of said jacket to said rectangular portion, a steam exhaust connection leading from said rectangular portion, and ribs on the front face of said rectangular portion, said box 80 85 having steam vents therethrough below said ribs.

4. In a shoe heater, a steam box comprising a substantially rectangular portion with ribs on its front face, a horizontal partition in said portion forming two separate chambers therein, baffles in said upper chamber to cause circuitous flow of steam therein, a series of arched members extending upwardly from the top of said rectangular portion to form individual shoe receiving chambers, the upper parts of said arched members having a double wall forming a steam jacket over said shoe receiving chambers, and steam connections for said jacket and the chambers in said 90 95 rectangular portion.

5. A shoe heater comprising a casing having in the upper part thereof a series of chambers to receive the toe portions of shoe lasts, the front wall of said casing having arched apertures therethrough opening into said 100 chambers, said apertures being of a size to accommodate lasts for men's shoes, a masking plate hinged on the front of said casing to swing in front of or clear of said apertures, said masking plate having openings therethrough registering with said apertures when the plate is swung to operative position and of a size to accommodate lasts for women's 105 shoes, a rack extending out in front of said casing to support the heel portions of shoe lasts, and means on said casing for securing said rack at selected heights relative to said apertures.

6. A shoe heater having a housing with arched apertures in the front wall thereof to receive the toe portions of shoes for men, and a masking plate having arched apertures therein to receive the toe portions of shoes for women, said plate being hinged to the 110 115 front wall of said housing to be swung into 120 125 130

and out of position over the apertures in said front wall.

7. In a shoe heater, a steam box having a ribbed upper surface, a hood over said upper surface forming a chamber to receive the toe portion of a last, said hood having a rear vent, and means for supplying a stream of vapor and heated air from below forward of said surface whereby said stream is drawn rearwardly across said surface, said ribs being arranged transversely with respect to the direction of flow of said stream:

8. In a shoe heater, a steam box, an arched jacket over the top of said box forming therewith a chamber with a lateral opening to receive the toe portion of a last, a steam supply connection attached to said jacket at an end thereof, a connecting passage from the remote end of said jacket to said box, and means for introducing a stream of vapor and air into said chamber.

In testimony whereof I have affixed my signature.
